UNITED STATES PATENT OFFICE.

ALFRED BEST, OF SALT LAKE CITY, UTAH.

VACUUM CLEANING DEVICE.

1,078,185.

Specification of Letters Patent. Patented Nov. 11, 1913.

Application filed December 6, 1912. Serial No. 735,334.

To all whom it may concern:

Be it known that I, ALFRED BEST, a citizen of the United States, residing at Salt Lake City, in the county of Salt Lake and State of Utah, have invented certain new and useful Improvements in Vacuum Cleaning Devices, of which the following is a specification.

My invention relates to attachments for suction or vacuum cleaning devices and has for its object to provide a device by means of which a carpet may be beaten and cleaned. Also to supply in the device a wind wheel by means of which the said beating device is operated, said wind wheel being rotated by the air currents which carry the dust. These objects I accomplish with the device shown in the accompanying drawings in which similar letters of reference indicate like parts throughout the several figures and as described in the specification forming a part of this application and pointed out in the appended claims.

Figure 1 is a plan of the device, portions shown in section and parts cut away. Fig. 2 is a section on line $\alpha\alpha$ of Fig. 1. Fig. 3 is a longitudinal section on line $y\gamma$ of Fig. 2. Fig. 4 is a transverse section on line $z\zeta$ of Fig. 3. Fig. 5 is a plan of one vane. Fig. 6 is a plan of a leaf therefor.

The invention consists of the novel construction and combination of parts in the drawings, in which the casing is made in an inverted T-shape, the horizontal portion thereof shown at 1 is cylindrical in form with the bottom portion flattened as at 2. Said portion 2 has a plurality of alined longitudinal slots 3 cut therein and transverse slots 4 alternately placed between the said slots 3. Mounted in said casing 2 is a horizontal shaft 5 and secured on said shaft is a pulley 6. Adjacent said transverse slots 4, the flexible whip members 7 are secured in said shaft 5 and to direct the free end of said whip members 7, disks 8 are secured on said shaft adjacent said whip members. In the vertical portion 9 of said casing a wheel case 10 is provided. Mounted in said case 10 is another horizontal shaft 11 on which another pulley 12 is intermediately secured and in alinement with said pulley 6. An endless belt 13 incloses said pulleys 12 and 6 whereby the rotary motion of said shaft 11 is imparted to said shaft 5. Secured on said shaft 11 are the radially disposed vanes 14. Each of said vanes 14 has a leaf 15 pivotally

secured on one of the radial edges thereof in order that when said vanes are moved against an air current the said leaves 15 will feather and when moved with or by the air current said leaves will open or spread and present a plane transverse to said current. Said wheel case 10 is larger in diameter than said vertical portion 9 of said case and positioned or placed partially without the plane of said vertical portion 9. The currents of air being drawn through said casing by any of the well-known suction means in the direction of arrow a will strike the vanes 14, and cause the pivoted leaves 15 thereof to open and form a plane and thereby rotary motion will be imparted to said wind wheel. When said wind wheel is rotated on its axis 11 the said shaft 5 will also be rotated by means of the pulleys and belt and the free end portion of the whip 7 will strike through the transverse openings 4 and beat the carpet, rug or other furniture over which said casing 1 is moved. The longitudinal slots 3 and transverse slots 4 furnish an ingress for loose particles of dust in said carpet, rug or other article of furniture as well as for the particles of dust that may be loosened by said whip 7.

I thus provide a mechanically operated means of beating a carpet and suction nozzle combined in one small device that may be manually moved over the carpet or rug and said carpet or rug cleaned without removal from the floor.

Having thus described my invention I desire to secure by Letters Patent and claim:

1. In a device of the class described the combination of suction means and of a casing attached thereto, having open alined longitudinal slots in the base of one portion; a horizontal shaft mounted in said casing above said slots; flexible whip members fastened in said shaft adjacent said open slots; a wind wheel mounted in another portion of said casing adapted to be rotated by air currents, induced by said suction means, through said casing; and means connecting said wind wheel and said horizontal shaft whereby the motion of said wind wheel will be imparted to said horizontal shaft.

2. In combination with the suction means of a vacuum cleaner; of a casing having open longitudinal and transverse slots in the base of one portion thereof; a shaft horizontally mounted in said casing above said

open slots; flexible whip members radially secured in said shaft in alinement with said slots; and means to rotate said shaft whereby the free ends of said whip members will be moved through said slots.

3. A device of the class described consisting of an inverted T-shaped casing having alined longitudinal slots and alternate transverse slots in the base thereof; a shaft horizontally mounted therein; flexible whip members radially secured in said shaft above said transverse slots; and means to rotate said shaft whereby the free ends of said whip members will be moved longitudinally in said transverse slots.

4. A device of the class described consisting of an inverted T-shaped casing having alined longitudinal slots and alternate trans-

verse slots in the base thereof; a shaft horizontally mounted therein; flexible whip members radially secured in said shaft above said transverse slots; and means to rotate said shaft whereby the free ends of said whip members will be moved longitudinally in said transverse slots, said means consisting of a wind wheel mounted on a counter shaft in said casing; a pulley on each of said shafts; and a belt connecting said pulleys whereby the motion of said wind wheel is imparted to said first mentioned shaft.

In testimony whereof I have affixed my signature in presence of two witnesses.

ALFRED BEST.
